UNITED STATES PATENT OFFICE.

JOHN FRANCIS BOORAEM, OF GREENWICH, CONNECTICUT.

PLUNGE-BATH TILE AND TERRA-COTTA CONSTRUCTION.

1,193,862.

Specification of Letters Patent. Patented Aug. 8, 1916.

Application filed June 16, 1915. Serial No. 34,331.

To all whom it may concern:

Be it known that I, JOHN FRANCIS BOORAEM, a citizen of the United States of America, and a resident of Greenwich, in the county of Fairfield and State of Connecticut, have invented certain new and useful Improvements in Plunge-Bath Tile and Terra-Cotta Construction, of which the following is a specification.

10 This invention relates to improvements in and relating to plunge bath tile and terra cotta construction, and has for an object to provide in such construction a tile unit provided with gripping means, to replace 15 the metal handles or rails heretofore in use, to enable the bathers to emerge from the bath.

A further object is to give to the plunge bath a more harmonious treatment than has 20 heretofore been possible with the metal rails used, and to provide such a construction which may be easily kept in a clean and sanitary condition.

With these and other objects in view, my 25 invention comprises the novel features, combination and arrangement of parts, hereinafter more fully described with reference to the accompanying drawings, and particularly pointed out in the claims.

30 In the drawings, Figure 1 is a perspective view partly in section of a plunge bath embodying my improved construction; Fig. 2 is a sectional view thereof; Fig. 3 is a perspective view partly in section of a modified form of my invention; and Fig. 4 is a 35 sectional view thereof.

Similar reference numerals indicate corresponding parts throughout the several views.

40 Referring to the drawings, and more particularly to Fig. 1 thereof, the plunge bath construction comprises the tile step or ladder units 10, the non-slipping floor tiles 11, the corner tiles 12 and 13 forming a gutter 14, 45 and the enameled bricks 15 forming the walls. Above the said ladder units is provided my improved gripping unit 16, having the overhanging portion 17, and provided with the inclined recesses 18, 19, forming hand grips. The surface of the unit 50 16 is flush with the surface of the floor. Channels 20, 21 serve to drain the water dripping in the recesses, into the gutter.

The ends of the channels, it will be noted, are obscured from view by means of the 55 overhanging portion 17 and the corner tiles 12. The said gripping unit may be of hollow construction, as shown in Fig. 2, or, if desired, other suitable known construction 60 may be employed.

In the form of construction shown in Fig. 3, two members 22 and 23 are provided with upright portions 24 and overhanging portions 25. The said upright portions are provided with an inclined surface 26 having a plurality of inclined recesses 27 therein forming hand grips for both the right and left hands. Each of the said recessed portions is provided with a channel 28, which connects with a main channel 29 having its outlet end under the overhanging portion 25, and thereby obscured from sight. 70

It will be seen that with my improved construction, a very convenient and sanitary gripping means is provided for use in 75 connection with the tile ladder or step construction of tile plunge baths, and because of its complete harmony with the general surroundings of such plunge baths will have a decidedly stimulating effect on the 80 esthetic sense of the bathers.

I have illustrated preferred and satisfactory forms of my invention, but it is obvious that changes may be made therein within the spirit and scope thereof, as defined in 85 the appended claims.

I claim:

1. A tile unit for plunge baths, comprising a plurality of exposed walls, in different planes, one of said walls being provided 90 with a recess forming a hand grip, and means connecting said recesses with another of said walls, to form a drain for said recess.

2. A tile unit for plunge baths, comprising an exposed front wall, a horizontally disposed exposed wall provided with recesses forming hand grips, and means connecting said recesses with said front wall to form a drain for said recesses. 95

3. In a tile unit for plunge baths, an exposed face provided with a recess forming a hand grip, and a channel connected to said recess and extending in a direction away from said exposed face to form a 105 drain for said recess.

4. A tile unit for plunge baths, comprising a front wall, an overhanging portion, an upper portion provided with a plurality of inclined recesses forming hand grips, and
- 5 means connecting said recesses with said front wall to form a drain for the said recesses.

In testimony that I claim the foregoing as my invention, I have signed my name in presence of two subscribing witnesses.

JOHN FRANCIS BOORAEM.
